(57) **CLAIM**

I claim the ornamental design for a display device, as shown and described.

DESCRIPTION

FIG. 1 is a front perspective view of a display device showing my new design, shown in a closed position;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a front perspective view of a display device showing my new design in which the display device is shown in an open position;

FIG. 9 is a front view thereof;

FIG. 10 is a rear view thereof;

FIG. 11 is a left-side view thereof;

FIG. 12 is a right-side view thereof;

FIG. 13 is a top view thereof;

FIG. 14 is a bottom view thereof;

FIG. 15 is a rear perspective view thereof; and,

FIG. 16 is an enlarged view of the encircled portion in FIG. 8.

The broken lines in the figures show portions of the display device which form no part of the claimed design.

The dot-dot-dash broken lines in the figures, encircling portions of the claimed design that are illustrated in enlargements form no part of the claimed design.

1 Claim, 12 Drawing Sheets
